INVENTOR

UNITED STATES PATENT OFFICE.

ALGERNON R. LYON, OF NARDIN, OKLAHOMA.

DEVICE FOR LOCKING WHIPS IN SOCKETS.

1,022,488.

Specification of Letters Patent.

Patented Apr. 9, 1912.

Application filed December 4, 1911. Serial No. 663,674.

To all whom it may concern:

Be it known that I, ALGERNON R. LYON, a citizen of the United States, residing at Nardin, in the county of Kay and State of Oklahoma, have invented certain new and useful Improvements in Devices for Locking Whips in Sockets; and I do hereby declare the following to be a full, clear, and exact description of the invention, such as 10 will enable others skilled in the art to which it appertains to make and use the same, reference being had to the accompanying drawings, and to the letters and figures of reference marked thereon, which form a part of 15 this specification.

This invention relates to new and useful improvements in means for holding whips in sockets and consists of a simple and efficient device of this nature, comprising a 20 plate which is fastened to the rim of the opening about the socket and to which a lock is rigidly fastened, having a tongue movable upon the plate and which is adapted to partially surround and frictionally 25 bind and hold the butt end of the whip.

The invention consists of various details of construction and combinations and arrangements of parts which will be herein-after fully described, shown in the accompanying drawings, and then specifically defined in the appended claim.

I illustrate my invention in the accompanying drawings, in which:-

Figure 1 is a perspective view showing 35 the application of my invention to a whip socket, and Fig. 2 is a top plan view.

Reference now being had to the details of the drawings by letter, A designates a whip socket of ordinary construction adapted to 40 be fastened to the dash board of a carriage and to the upper end of the socket is secured an apertured plate B which has a circular-outlined flange D fitting over the top of the socket. Said plate extends laterally 45 from the socket, and E is a padlock which

is rigidly fastened thereto or integral with the plate and is provided with a tongue F having a semi-circular outlined portion adapted, when the tongue is in a locked relation within the casing of the pad lock, 50 to bind against the butt end O of a whip and hold the same against the concaved marginal edge of the opening in the plate also against the marginal edge of a concaved recess formed in the end of the casing of the 55 padlock. A stop T is formed upon said plate and is adapted to limit the movement of the shackle in one direction.

The operation of the device will be readily understood and is as follows: When the 60 lock is in an open relation, the tongue will be thrown out by the spring of the lock to its limit and against said stop, thus allowing the butt of a whip to be inserted in the socket, after which the tongue may be 65 pushed into the casing and the lock and frictionally engaging the butt of the whip to hold the same securely in place without rattling.

What I claim to be new is:- 70

A device for holding whips in sockets comprising, in combination with a whip socket, a plate provided with an integral flange fitting over said socket and an opening for the reception of the butt end of a 75 whip, said plate having a lateral extension which is flush with the face of the plate, a lock casing fixed to said projection, said casing having a pivotal tongue at its end provided with a concaved recess which is 80 flush with the marginal edge of the opening in said plate, a stop projecting from the latter and adapted to limit the swinging movement of the tongue, as set forth.

In testimony whereof I hereunto affix my 85 signature in the presence of two witnesses.

ALGERNON R. LYON.
